UNITED STATES PATENT OFFICE.

EDWARD O. KRAEPELIN, OF BOTSFORD, CONNECTICUT.

EGG-CARRIER.

1,205,753.

Specification of Letters Patent. Patented Nov. 21, 1916.

Application filed September 20, 1915. Serial No. 51,517.

To all whom it may concern:

Be it known that I, EDWARD O. KRAEPELIN, a citizen of the United States, residing at Botsford, county of Fairfield, State of Connecticut, have invented an Improvement 5 in Egg-Carriers, of which the following is a specification.

This invention has for its object to provide an egg-carrier of the type in which each 10 egg is held in an independent, suspended pocket, which will fully meet the requirements of the trade so far as protection of the eggs is concerned and in which the cost of construction, *i. e.* cost of material and 15 cost of assembling, shall be reduced to the minimum.

With these and other objects in view, I have devised the novel egg-carrier which I will now describe, referring to the accompanying drawing forming a part of this 20 specification, and using reference characters to indicate the several parts.

Figure 1 is a perspective view of my novel egg-carrier, partly broken away, illustrating 25 the construction and mode of use; Fig. 2 a cross section thereof on an enlarged scale; Fig. 3 a perspective view, on the same scale, of an egg pocket detached, and Fig. 4 is a perspective view of another form of egg 30 pocket which permits the diagonal wall to be dispensed with.

10 denotes the body or frame of my novel carrier, which is simply a strip of corrugated strawboard of sufficient width to accommodate the pockets and of sufficient 35 length, when bent to rectangular form and the ends secured together, to accommodate the required number of egg pockets placed side by side, for example six or twelve.

40 11 denotes a supporting strip made of relatively strong paper, which is placed longitudinally of the frame, extending from end to end and diagonally from an upper corner to a lower corner, and is made of sufficient 45 width to provide flaps 12 which are folded over the top and bottom edges respectively of the frame and are pasted or otherwise secured to the outer side thereof, as clearly shown.

50 13 denotes the egg pockets which are likewise made of relatively strong paper.

In the form illustrated in Figs. 1, 2 and 3, the pockets are made from pieces of paper approximately square and provided with 55 flaps 14 which are pasted to the supporting strip with their lower ends overlapping, as

shown in Fig. 3, and their upper ends diverging so as to form an approximately cone-shaped pocket, the lower end of which is closed by an oblique fold 15 lying against the side of the wall. The upper end of the pocket is left open, as shown in Figs. 1 and 3, and in dotted lines in Fig. 2, and when the egg is placed therein, is folded down upon it, as at 16 in Figs. 1 and 2, to close 60 the pocket and yieldingly retain the egg in place.

An important feature of my present invention is that everything about it is elastic or resilient and yields in such a manner 65 as to prevent the shocks inseparable from transportation from being transmitted to the eggs. The frame itself, while sufficiently rigid after assembling, for the purpose intended, is elastic and yields appreciably. 70 The supporting strip, while it does not stretch, yields with the yielding of the frame, and the upper and lower closing folds, indicated by 15 and 16, also yield appreciably, so that while each egg is securely 75 held in place, the shocks and jars of transportation are taken up by the carrier and not transmitted to the eggs.

In Fig. 4, I have illustrated another form 80 of egg pocket which is provided with flaps 85 17 which are folded over the top and bottom edges respectively of the frame and are pasted to the outer side thereof or to the outside of the supporting strip, if used. In this form the supporting strip is not necessary, and may or may not be used, as preferred. 90 The lower end of the pocket is closed flatwise, and the upper end thereof is provided with a closing flap 18, which is folded down upon the egg to close the 95 pocket and yieldingly retain the egg in place.

In use, the carriers may be shipped singly or a number of them may be placed in a suitable box or carton and shipped as a single package.

Having thus described my invention I claim:

1. An egg carrier comprising a frame 105 formed with side and end walls, and a plurality of individual egg pockets of flexible material, each provided with a flat wall attached to said frame and extending diagonally across the same from top to bottom, and a lower portion folded to lie against 110 one of said walls.

2. An egg carrier comprising a frame

formed with side and end walls, and a plurality of individual egg pockets of suitable material each provided with a flat wall extending diagonally across the frame from 5 top to bottom, and a lower portion folded to lie against one of said walls, said diagonal portion having flaps attached to opposite sides of said frame.

3. An egg carrier comprising a frame of 10 rectangular form, a supporting strip extending from end to end and diagonally from an upper corner to a lower corner of the frame, and a plurality of independent pieces of flexible material attached to said 15 supporting strip and folded to form egg pockets, said strip forming one wall of each pocket.

4. An egg carrier comprising a frame of 20 rectangular form, a supporting strip extending from end to end and diagonally from an upper corner to a lower corner of the frame, and a plurality of independent pieces of flexible material attached to said supporting strip and folded to form egg 25 pockets, said strip forming one wall of each pocket, the lower portion of the material

forming each pocket being folded to lie against one of the walls of said frame.

5. An egg-carrier comprising a frame 30 formed from a strip bent to rectangular form and the ends secured together, a supporting strip extending from end to end and diagonally from an upper corner to a lower corner of the frame, and egg pockets 35 formed from pieces of paper approximately square and provided with flaps which are secured to the supporting strip with their lower ends overlapping and their upper ends diverging, forming pockets, the upper and lower ends of which are closed by folding 40 the material of the pockets.

6. An egg-carrier comprising a frame 45 formed from a strip of corrugated straw-board, a supporting strip of paper extending diagonally of the frame and egg pockets 50 formed from paper and secured to the supporting strip, the lower ends of said pockets being closed by an oblique fold and the upper ends by folding the material of the pockets downward.

In testimony whereof I affix my signature.
EDWARD O. KRAEPELIN.
